[57] CLAIM

The ornamental design for a foot splint or the like, as shown and described.

DESCRIPTION

FIG. 1 is a top plan view of a foot splint or the like, showing our new design;

FIG. 2 is a rear elevational view thereof;

FIG. 3 is a side elevational view thereof, the opposite side being identical thereto;

FIG. 4 is a bottom plan view thereof;

FIG. 5 is a front elevational view thereof; and

FIG. 6 is a perspective view thereof.
